UNITED STATES PATENT OFFICE.

FREDERICK L. WATTERS, OF SHELBY, OHIO.

DESIGN FOR A CHAIR-BACK.

No. 39,546.

Specification for Design.

Patented Sept. 15, 1908.

Application filed June 15, 1908. Serial No. 438,687. Term of patent 14 years.

To all whom it may concern:

Be it known that I, FREDERICK L. WATTERS, a citizen of the United States, residing at Shelby, in the county of Richland and State of Ohio, have invented a new, original, and ornamental Design for a Chair-Back, of which the following is a specification, reference being had to the accompanying drawing, forming a part thereof.

The figure is a front elevation of a chair back, showing my new design.

I claim:

The ornamental design for a chair back, as shown.

FREDERICK L. WATTERS.

Witnesses:

C. S. WATTERS,
J. H. BRACKNEY.
